* cited by examiner

Primary Examiner — Leanne Was-Englehart

(74) Attorney, Agent, or Firm — Jason T. Daniel, Esq.;
Daniel Law Offices, P.A.(57) CLAIM

The ornamental design for a splash pad with anchor system, as shown and described.

DESCRIPTION

FIG. 1 is a perspective view thereof,

FIG. 2 is a right side view thereof,

FIG. 3 is a front side view thereof,

FIG. 4 is a back side view thereof; and,

FIG. 5 is a top side view thereof.

The broken lines depict portions of the splash pad with anchor system that form no part of the claimed design.
The right side is a mirror image of the left side.
